PAPER ROLL HOLDER OR THE LIKE

Russell K. Swanson, Kansas City, Mo., assignor to Central Molding and Manufacturing Company, Kansas City, Mo., a corporation of Missouri

Filed July 26, 1965, Ser. No. 86,278

Term of patent 14 years

(Cl. D41—1)

FIG. 1 is a top plan view showing one form of a paper roll holder or the like;

FIG. 2 is a front elevational view thereof;

FIG. 3 is an end elevational view thereof;

FIG. 4 is a top plan view showing a further form of a paper roll holder or the like;

FIG. 5 is a front elevational view thereof;

FIG. 6 is a view of one end thereof; and

FIG. 7 is a view of the opposite end thereof.

The dominant portions of my design reside in those portions shown in full lines.

I claim:

The ornamental design for a paper roll holder or the like, substantially as shown and described.
